UNITED STATES PATENT OFFICE.

HARRY W. RHINELANDER, OF FREEDOM, PENNSYLVANIA.

SAFETY-APRON FOR LOCOMOTIVES.

1,306,438.

Specification of Letters Patent. Patented June 10, 1919.

Application filed October 2, 1918. Serial No. 256,570.

To all whom it may concern:

Be it known that I, HARRY W. RHINELANDER, a citizen of the United States, residing at Freedom, in the county of Beaver 5 and State of Pennsylvania, have invented certain new and useful Improvements in Safety-Aprons for Locomotives, of which the following is a specification.

This invention relates to attachments for 10 locomotives and more particularly to a safety apron device constructed in a manner to eliminate bolts and hinge pins such as are commonly employed to pivotally mount the ordinary locomotive apron in position.

15 One of the primary objects of this invention is to provide an improved safety apron adapted to extend from the locomotive to the tender and gap the space therebetween, and be mounted so that it may be swung upwardly to inoperative position in a manner similar to the hingedly mounted apron, but which will be devoid of any hinged connection; and which may be readily dismantled when the apron is to be removed.

20 25 A further object of this invention is the provision of a device of this character which consists of comparatively few parts and is simple in construction but durable and well adapted to withstand the rough usage to 30 which devices of this character are ordinarily subjected.

For a full description of the invention and the advantages and merits thereof, reference is to be had to the following description and 35 accompanying drawings, in which:—

Figure 1 is a view in side elevation showing the invention in operative position.

Fig. 2 is a detail section through the device constructed in accordance with my invention.

Fig. 3 is a plan view of one of the elements used to support the apron.

Fig. 4 is a perspective view of a complementary element.

45 Referring to the drawings, wherein is illustrated the preferred form of my invention, in which like numerals of reference indicate corresponding parts throughout the several views, the locomotive indicated 50 at A is coupled to the tender B in the usual manner. The gap between the locomotive and tender is of considerable width and is ordinarily bridged by the apron 1 which usually consists of a metallic plate having 55 hinged connection to the locomotive and adapted to rest upon the bolster C. It has

been found, however, that the bolts and pintles and hinge pins generally employed to hingedly connect the apron 1 to the locomotive, become worn in time and by virtue of the strain upon them, will break and drop out of position whereupon the apron will drop upon the trackway between the locomotive and pintle and oftentimes be the cause of derailing the tender thereby resulting in 60 serious accident. Pivotal connection of the apron 1 with the locomotive, therefore is entirely avoided by the present structure, which, as shown to advantage in Fig. 2 of the drawing, includes a fastening plate 2 which is bolted, riveted or otherwise suitably fastened to the locomotive A. This plate has extending therefrom an arcuate sleeve 4 which projects through an arc equal to a quarter circle. The interior of the sleeve 4 is hollow and may be either round or square, the present illustration showing the same as square. The apron 1 has attached thereto the complementary connecting member 5 shown in detail in Fig. 4 of the drawing 70 and which includes the fastening plate 6 adapted to be rigidly fastened to the apron 1 and the arcuate arm 7 which is shaped to fit within the sleeve 4 as shown. In this manner the members 7 and 4 are telescopically 75 connected so that the member 7 slides within the member 4 as the apron 1 is opened and closed. The dotted lines in Fig. 1 indicate the manner of opening the apron so that the two telescopically connected members 7 and 4 will maintain the apron in position until the latter is opened to its full position whereupon it may be removed and de-mounted. To place the apron back into 80 position it is merely necessary to place the member 7 within the open end of the sleeve 4 and permit the apron to drop into the position shown so that one edge will be supported by the bumper C while the other end is supported by the telescopically connected 85 members as shown in Fig. 2.

Thus it will be seen that no bolts, rivets, hinge pins, or pintles are employed in establishing the hinged connection yet the apron is adapted to swing in the same manner as is the case when the hinge is used. Furthermore the apron may be readily removed at all times without resorting to the necessity of removing hinge pins or pintles as is the case with the ordinary device.

105 110 The foregoing description and accompanying drawings have reference to what might

be considered to be the preferred or approved form of my invention. I desire it to be understood that I may make such changes in the construction, combination and arrangement of parts, materials, dimensions et cetera, as may prove expedient and fall within the scope of the appended claims.

Having thus fully described my invention what I claim as new and desire to secure by 10 Letters Patent is:—

1. A device of the class described, the combination of a locomotive and tender, and an apron adapted to bridge the space between the locomotive and tender and a supporting member attached to the locomotive and including an arcuate sleeve, and a complementary member fixed to the apron and having an arcuate arm adapted to be telescopically received in the said sleeve to permit rela-

tive swinging movement of the apron with respect to the said locomotive, and to support one end of the apron when the latter is in operative position.

2. A locomotive apron comprising an apron plate having an arcuate arm fixed thereto and depending from the bottom of the same, and a complementary supporting element comprising a fastening plate having an arcuate sleeve adapted to receive the said arm to permit relative sliding movement of the arm within the sleeve whereby the said apron may be swung through an arc.

In testimony whereof I affix my signature in presence of two witnesses.

HARRY W. RHINELANDER.
